UNITED STATES PATENT OFFICE.

CURTIS O. LUCE, OF BRANDON, VERMONT.

IMPROVEMENT IN SKATES.

Specification forming part of Letters Patent No. 38,591, dated May 19, 1863.

To all whom it may concern:

Be it known that I, C. O. LUCE, of Brandon, in the county of Rutland and State of Vermont, have invented a new and useful Improvement in Skates; and I do hereby declare that the following is a full, clear, and exact description of the same, reference being had to the accompanying drawings, making a part of this specification, in which—

Figure 1 is a side sectional view of my invention, taken in the line $x x$, Fig. 2; Fig. 2, a transverse vertical section of the same, taken in the line $x' x'$, Fig. 1.

Similar letters of reference indicate corresponding parts in the two figures.

To enable those skilled in the art to fully understand and construct my invention, I will proceed to describe it.

A represents the runner of the skate, which may be of the usual or any proper form, and C is a plate on which the ball or front part of the foot rests. This plate C has a pendent bar, D, projecting down centrally from it, the lower end of said bar being slotted vertically, so as to fit on the upper part of the runner, to which it is secured by a pivot, a. The bottom of the slot b in the bar D rests on the upper edge of the runner, and said bottom is curved in the form of a rocker, as shown in Fig. 1, so as to admit of the plate C working or rocking on the pivot and runner. The pendent bar forms what is commonly termed a "post" or "knee," and it keeps the plate C at a proper height above the runner.

The plate C may be constructed of metal plate, or it may be of malleable cast-iron, and it has two openings, c c, in it at its front and back parts. Through these openings straps E E' pass, and the upper surface of the plate has transverse recesses d d in it, said recesses being in line with the openings c c in order to receive the portion of the straps which is between, and cause the same to be "flush" with the upper surface of the plate C, as shown clearly in Fig. 2. At the center of each recess d there is a spur, e, and these spurs pass through the straps and prevent the same, as

well as the skate, from shifting laterally when the skate is attached to the feet. The two straps E E' are at such a distance apart that when the strap is attached to the foot the front strap, E, will be in front of the joint of the great toe, and the strap E' behind it. By this means the skate may be firmly attached to the foot of the wearer, and the foot at the same time will be allowed to work freely and will not be cramped, so as to render the wearer or skater uncomfortable, as is most generally the case with the ordinary strapped skate. The yielding or working of the plate C also serves to greatly promote the ease and comfort of the skater.

F represents the heel-plate, which has a pendent bar, G, attached about centrally to it. The lower end of the bar G is slotted vertically, so as to fit on the upper part of the runner A, but not like the pendent bar D of the plate C to work on the runner, the plate F being stationary and the bar G secured to the runner by a pivot, f. The heel-plate is provided at its back edge with a curved upright flange, g, to fit against the back part of the heel of the boot or shoe, and said plate has two openings in it for the heel-strap H to pass through, said strap being buckled around the instep of the wearer or skater. The flange g prevents the heel of the boot or shoe on the skate from slipping laterally.

Having thus described my invention, what I claim as new, and desire to secure by Letters Patent, is—

1. The recesses d d in the upper surface of the plate C, in combination with the strap-holes c and spurs e, substantially as and for the purposes herein specified.

2. The heel-strap H and heel-plate F, when used in connection with the adjustable plate C and the straps E E', for the purpose herein specified.

CURTIS O. LUCE.
